UNITED STATES PATENT OFFICE.

REES W. PRICE AND HENRY A. RUSSELL, OF OSKALOOSA, IOWA.

SIGNAL-FLAG STAFF.

SPECIFICATION forming part of Letters Patent No. 363,345, dated May 17, 1887.

Application filed June 17, 1886. Serial No. 205,472. (No model.)

To all whom it may concern:

Be it known that we, REES W. PRICE and HENRY A. RUSSELL, of Oskaloosa, in the county of Mahaska and State of Iowa, have 5 invented a new and useful Improvement in Signal-Flag Staffs, of which the following is a specification.

Our invention consists in an improved signal-flag staff, designed to be used on engines, 10 trains, and by switchmen on railroads in exhibiting signal-flags of different colors, and which will be hereinafter fully described and claimed.

Referring to the accompanying drawings, 15 Figure 1 is a perspective view of our improved flag-staff. Fig. 2 is a longitudinal central sectional view of the same. Fig. 3 is an end view of the lower end of the hollow staff with that end cap removed, and Fig. 4 is a detail perspective view of the lower end of one of the rods with its attachments.

The same letters of reference indicate corresponding parts in all the figures.

Referring to the several parts by letter, A 25 indicates the hollow flag-staff, which is in the form of a cylinder, and is closed at each end by the end caps, B B. This cylinder may be made of any desired material, although tin or very light sheet metal is preferable. In the 30 lower end of this hollow staff are secured the small brackets C, which form bearings for the lower ends of the rods around which the flags are wrapped. These rods D may be of any desired number, according to the number of

35 flags which it is desired to use; but in the accompanying drawings we have shown three of these rods and flags, and the upper ends of these rods are seated in bearings E, formed on the inner side of the upper cap-piece of the 40 staff, while their lower ends turn in apertures C' in the brackets C, the extreme lower ends of the rods bearing against the lower end cap of the staff. The upper portion of each rod is preferably enlarged, or may have a wooden 45 sleeve, F, secured concentrically thereon, while around the lower portion of each rod is placed a coiled spring, G, the upper end of which is rigidly secured by passing it through a small hole, G', in that portion of its rod, and bending 50 it around the same, while its lower end is secured in a similar manner, as shown, to the

stationary bracket in which the lower end of its rod is journaled. On the lower end of each rod, immediately above the bracket in which it is journaled, is immovably secured a ratchet-wheel, H, having the inclined teeth H', and a centrally-pivoted pawl, I, pivoted on the upper side of each bracket, engages with the inclined teeth of this ratchet-wheel, and is normally held in engagement therewith through 60 the influence of a small coiled spring, J', which encircles the outer portion of a pin, J, which works in an opening, A², in the lower end of the casing A, and is pivotally secured at its inner end to the rear end of the centrally-pivoted pawl I, the spring J' being coiled around that portion of each pin between its headed outer end and the outer side of the hollow staff A, a washer, J², being preferably placed between the lower end of each spring J' and the 70 outer side of the staff.

Around the upper enlarged portion of each rod is wrapped a flag, K, the inner end of which is secured to its rod, the three flags being of different colors—one red, one white, and 75 one green—and the hollow cylindrical staff A is formed with the longitudinal slots A', of sufficient length each to admit of the flag which is next to it passing readily through it. The outer end of each flag is passed through its 80 registering-slot in the staff, and is formed with an enlargement, K', which prevents the outer end of the flag being drawn inside of the staff when the spring G operates to wrap it around its rod.

85 The operation of our invention is as follows: When the switchman or other operator by the side of the track or on the train desires to display a signal-flag of a certain color, he catches hold of the outer end of the particular flag 90 which he desires, and draws it out of the hollow staff through its slot until it is fully displayed. As the flag is thus unwrapped, the rod on which it is mounted is of course rotated, and thus winds up or coils tightly the 95 spiral spring encircling its lower portion and secured thereto by its upper end and at its lower end to the bracket secured to the inner side of the lower end of the casing, the spring-actuated pawl engaging with the inclined teeth 100 of the ratchet-wheel on the rod, and thus holding the rod firmly at the point of its rotation

to which it is drawn by the unwrapping of the flag. When the operator desires to withdraw the flag within the hollow staff, he presses with his finger or thumb upon the pin J of that rod, 5 thereby turning the centrally-pivoted pawl, so as to free its operative end from the inclined teeth of the ratchet-wheel secured upon the lower end of the rod, when the spiral spring, rapidly uncoiling to its normal position, will 10 rotate its rod, so as to wrap the flag smoothly and rapidly around it, thus withdrawing the flag within the hollow staff until its enlarged outer end comes in contact with the jaws of the slot.

15 From the foregoing description, taken in connection with the accompanying drawings, the construction, operation, and advantages of our invention will be readily understood. It will be seen that it is exceedingly simple 20 and strong in construction, and therefore not liable to get out of order, and that it is very efficient in its operation. Its use dispenses

with the necessity of keeping three separate flag-staffs and flags, and combines the three in one staff, so that they are always at hand and ready for instant use, which is a most important feature.

Having thus described our invention, what we claim, and desire to secure by Letters Patent, is—

In a signal-flag staff, the combination of the cylinder having the longitudinal slots and provided with the bearings at its upper and lower ends, the rods having the ratchet-wheels at their lower ends, the spiral springs, and the 35 spring-actuated pawls having the outwardly-extending releasing-pins, all constructed and arranged to operate in the manner and for the purpose herein set forth.

REES W. PRICE.
HENRY A. RUSSELL.
